Primary Examiner — Kendra Leslie Hamilton(74) *Attorney, Agent, or Firm* — Dragon Sun Law Firm, PC; Jinggao Li, Esq.(57) **CLAIM**

The ornamental design for a feeding bottle, as shown and described.

DESCRIPTION

FIG. 1 is a front, right perspective view of a feeding bottle showing my new design;

FIG. 2 is a rear, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof; and,

FIG. 9 is an enlarged view of the selected portion 9 in FIG. 6.

The broken lines shown in the figures depict portions of the feeding bottle that form no part of the claimed design.

1 Claim, 9 Drawing Sheets(56)
